UNITED STATES PATENT OFFICE.

LEWIS E. MYERS AND ARTIE C. CARLSON, OF VALPARAISO, INDIANA, AND CARL S. BATES, OF CHICAGO, ILLINOIS, ASSIGNEES, BY MESNE ASSIGNMENTS, TO THE NORTHERN TRUST COMPANY AND HAROLD H. ROCKWELL AS TRUSTEES.

WHEELED TOY.

Application filed December 21, 1925. Serial No. 76,597.

Our invention relates to improvements in wheeled toys, and it more especially consists of the features pointed out in the annexed claims.

5 The purpose of our invention is to provide a three wheeled toy in the coaster wagon class, whose body simulates an airplane fuselage or the form of an animal; that has a seat for the rider to sit astride of the body; that 10 has a direct connected two-pedal crank shaft rigidly attached to the one driving wheel and loosely connected to the other; that has the driving wheels located at the front, and the steering wheel at the rear end making a 15 reversed tricycle; that in the airplane form has a streamline fuselage, wings, rudder, landing wheels, and a steering wheel taking the place of a tail-skid; that provides an adjustable seat in the "cockpit"; that is 20 sturdy in construction and pleasing in appearance; that has self-limiting stops in its steering mechanism; that in the airplane type combines the rudder with the steering wheel; that can be readily shipped in knock- 25 down shape; that provides a separate unitary wheel support on each side of the fuselage which makes provision for ample foot room above the pedals; and that also provides the steering rod and hand wheel at a 30 conventional angle so as to give the ensemble a pleasing racing appearance.

With these and other ends in view, we illustrate in the accompanying drawing such instances of adaptation as will disclose the 35 broad underlying features of our invention without limiting ourselves to the specific details shown thereon and described herein.

Figure 1 is a side elevation.

Fig. 2 is a top plan view.

40 Fig. 3 is a diagrammatic plan view of the steering control, showing the extreme adjustment in dotted lines.

Fig. 4 is a perspective view of the steering rod connection to the steering link.

45 Fig. 5 is an elevation of the steering wheel detached from the body—looking rearward.

Fig. 6 is a front elevation of Fig. 1.

Fig. 7 is an enlarged plan view, in section, of the steering rod positioned between the 50 two halves of the body.

Fig. 8 is a diagrammatic front elevation showing a central crank shaft bearing.

Fig. 9 is a side elevation in section of the steering wheel structure.

Fig. 10 is a diagrammatic side elevation 55 showing a simulated animal body.

Fig. 11 is a diagrammatic front elevation of modified wheel supports.

Fig. 12 is a top plan view of the steering wheel structure.

In practically carrying out our invention we may use such alternative expedients as the exigencies of hard use, and the necessities of manufacture may demand, without departing from the spirit of our invention. 65

We may construct our wheeled toy with any suitable shaped body 1, which as shown in Fig. 1 simulates an airplane fuselage; and at 41 in Fig. 10, the body of a horse. In the latter case the wings 33 may be omitted 70 unless it is desired to have pegasus equipped with the wings of mythology. It is of course obvious that the body 1 may be shaped to represent different animals and almost an unlimited variety of objects. The 75 body has a seat 2 grooved on its underside and fastened with screws 38 so that its position can be adjusted by changing the screws into other holes 42, shown in dotted lines in Fig. 1. The body is made in two halves, as shown in Fig. 7. These halves are held together and in engagement with the wheel supports 6 by bolts 9, and also by the bolts 20 at the rear end of the body. 80

The body 1, of whatever form it may be 85 made, is mobile through the use of a driving wheel and a loose wheel 3 placed one on each side of the body near its front end. A steering wheel 10 supports the rear end of the body and at the same time serves as a means by which the body is turned sideways when the wheels 3 are rotated. This is accomplished by a one-piece crank 4 rigidly secured to one wheel and loosely connected to the other, and the pedals 5 mounted on the crank. Each wheel 3 has its own 90 unitary support 6 connecting it with the body. These supports are curved downward and slightly rearward terminating in crank shaft ends 7. The portions 6 and 7 100 form an arch, as shown in Fig. 6, that gives ample clearance for the user's foot when a pedal 5 is at its highest point. The straight portions 8 of the wheel supports pass vertically alongside of the body to which they are secured by the bolts 9. When wings 33 are attached to the body, parts 8 of the wheel supports are bent outward at 34 and are re-

inforced by braces 35 to form a support for the wings.

The steering rod 26 is located in grooves formed on the inside faces of the two-part body 1, as shown in Fig. 7. The upper end of the steering rod 26 is supported in a bearing 29 and the lower end is supported in a bearing 28 secured to the under side of the body, as shown in Fig. 4. Cotter pins 30 10 located above the bearing 29 and below the bearing 28 hold the steering rod in its proper lengthwise relation, so that the steering wheel 32 and the steering crank 27 remain in their required position. This rod and 15 its attached hand wheel is placed at an angle so that the wheel will be more accessible to the user, and at the same time will also have a more pleasing appearance. To further carry out the matter of appearance in simulating an airplane, we may position a propeller 36 on a bearing pin 37 at the front end of 20 the body. This propeller being free to rotate on the pin 37 is easily set in motion as the wheels carry the body forward at a 25 greater or less speed.

As a matter of safety, we have provided arbitrary limit stops so that a movement of the steering wheel 32 cannot be so great as to put the "rudder hard over". This is accomplished, in one direction, when the steering link 16 pivoted to the crank 27 on pin 31 engages the steering rod 26, as shown in dotted lines in Fig. 3; and, in the other direction, when the steering link 16 engages 35 the steering fork 13, as shown in full lines in the right hand portion of Fig. 3. These limit stops prevent the upsetting of the device when a sharp turn is being made either to the right or to the left.

40 It is of course understood that the steering mechanism is one of the important features of our invention. The structure which is exemplified in the drawing comprises a steering post 11 secured in the steering fork 12 against turning. Its lower end may be riveted to the steering fork brace 13, as shown in Figs. 5 and 9. On top of the steering fork 12 a bearing boss 14 may be placed, on which the weight of the rear end 45 of the body rests. A steering link bracket 15 is secured to the steering fork 12 on its left hand side. In this connection it will be noted that the crank 27 of the steering rod 26 projects toward the right hand side 50 of the body, which places the steering link 16 at an angle, as shown in Fig. 2. This relation causes the body to swerve in the same direction that the steering wheel 32 is turned.

55 The steering pin 11 is pivotally attached to the body by means of a plate 18 and its upper and lower bearing ears 17 in which the pin 11 has rotary movement. The plate 18 has side extensions 19, between which the 60 body 1 terminates, where it is held by

bolts 20. In order that the rudder 23 or the tail 25 will swing sidewise with the steering wheel 10, these extremities are secured to the steering pin 11 by means of a U-shaped plate 21, as shown in section 70 at A and in plan at B of Fig. 9. The plate 21 is fastened to the pin 11 by means of a bolt 22, and the plate 21 is secured to the rudder or other extremity by bolts 24.

A modified form of wheel supports is 75 shown in Fig. 11, wherein these supports are arched as indicated at 40, so as to provide additional foot room if extra clearance space is required. A further alternative construction is shown in Fig. 8 wherein a 80 central crank shaft bearing 39 is attached to the underside of the body.

From the foregoing description it will be seen that our device is sturdy in construction, unique in appearance and function and 85 possessed of many recreational possibilities.

It is to be understood that we may also make the body 1 of metal, approximating a round shape in cross section, or any departure from the flat form shown. 90

What we claim is:

1. As an article of manufacture, a body simulating a desired object, a crank shaft beneath the body at its front end, suitable 95 separate unitary supports from the body to opposite ends of the crank shaft, a rigidly connected wheel and a free wheel on the crank shaft, a trailing steering wheel pivotally attached to the rear end of the body, an adjustable seat located on the body between the front and rear end, a steering rod and attached wheel positioned in the body forward of the seat, and a link connecting the steering rod and the steering wheel respectively on opposite sides of the body. 100

105 2. In wheeled toys, a one-piece body, a seat thereon, a steering wheel forward of the seat, a pair of wheels beneath the body at its front end, supports from the wheels to the body, a crank shaft positioned in the lower ends of such supports, said shaft being rigidly connected to one wheel and loosely connected to the other wheel, pedals on the crank shaft, a trailing steering wheel pivoted to the body for horizontal movement, a steering rod for the steering wheel passing diagonally through the body, connecting means from the lower end of the steering rod to the trailing steering wheel, and means on the steering rod and trailing steering wheel pivot adapted to limit the steering movement of the steering wheel. 110

115 3. In wheeled toys, a thin single member body positioned with its narrow dimension vertical, a pair of wheels beneath the body, separate supports from each wheel to the body, a crank shaft rotatable in the lower ends of such supports, pedals on the crank shaft for applying power to one of the 120

125

wheels, a seat on the body, a steering wheel forward of the body, a steering rod passing diagonally through the thin body and connected to the steering wheel, a vertical pivot at the rear of the body, a trailing steering wheel support movable in such pivot, a trailing steering wheel rotatable in the support, a simulated rudder secured to the support

for simultaneous movement on a horizontal plane, and means for connecting said support to the lower end of the steering rod. 10

In testimony whereof we affix our signatures.
